BAKING OVEN

Louis D. Houlis, Seattle, Wash.

Application September 7, 1934, Serial No. 743,045

5 Claims. (Cl. 107—59)

This invention relates to new and useful improvements in baking ovens.

One object of the invention is to provide an improved baking oven which may be fired by fuel or Diesel oil, or natural or artificial gas.

5 An important object of the invention is to provide an improved firing or heating unit for a baking oven which has a maximum radiating surface and is so constructed that overheating, and resultant burning out of the system, is prevented.

10 Another object of the invention is to provide an improved firing unit for a baking oven which includes means for automatically recirculating a portion of the gases after they have cooled to some extent due to their first circulation through the unit, this recirculation of the cool gases serving to prevent overheating of the heating unit and being accomplished without the aid of an auxiliary recirculating fan.

20 Another object of the invention is to provide an improved firebox having a Venturi opening at its forward end through which the fuel to be burned is injected, said opening being constructed so as to vent or suck in any cool gases which may be passed thereby.

25 A further object of the invention is to provide a heating unit for a baking oven including a firebox connected with a flue system through which the hot gases are circulated, and means for conducting the cooled gases, after their circulation, past the admittance opening in the firebox, whereby said cooled gases are sucked into said firebox and reheated and recirculated; the entrance of said cool gases serving to prevent overheating of the firebox and burning out of the unit.

30 Still another object of the invention is to provide an improved firebox having a Venturi opening in its forward end through which the fuel is injected, and having a conical outlet opening in its rear end, whereby the hot gases escaping from said opening are deflected inwardly so as to prevent them from contacting the metal walls of the flue system immediately upon escape from the firebox; said opening being so constructed as to also reflect a shadow in the immediate vicinity of the gas outlet, whereby firebox reflection is dulled and the forward portion of the firebox is kept cooler.

35 A still further object of the invention is to provide an improved heating unit for a baking oven which is so constructed that the cooled gases are automatically recirculated, whereby the efficiency is increased and the life of the unit prolonged.

40 Another object of the invention is to provide

an improved heating unit including a firebox which is so arranged that the firebox is the only portion constructed of refractory material, the remainder of the unit being metal, thereby reducing the cost of manufacture and increasing radiation and heating efficiency of the unit.

45 A construction designed to carry out the invention will be hereinafter described together with other features of the invention.

The invention will be more readily understood from a reading of the following specification and by reference to the accompanying drawings, in which an example of the invention is shown, and wherein:

50 Figure 1 is an isometric view of a baking oven constructed in accordance with the invention and having a portion broken away to show the firing unit, which is shown partly in elevation and partly in section,

Figure 2 is a transverse vertical sectional view, taken on a line through the firebox, and

Figure 3 is a horizontal, cross sectional view, taken through the flues.

55 In the drawings, the numeral 10 designates an oven which may be of any desired shape or structure. The oven is shown as being substantially rectangular in shape and has the usual insulated walls 11 and bottom 12. A vertically sliding door 13 is provided in the front wall for easy accessibility to the interior of the oven and the usual revolving reel 14 is mounted within said oven. The articles to be baked are placed on the reel and the heating unit 15 is mounted on the floor of the oven beneath the reel.

The heating unit is an important feature of the invention and comprises a firebox 16 which is positioned at one end of the oven near the rear wall thereof, a sinuous flue 17, a return passage 18 connecting the end of the flue with the inlet opening of the firebox and an outlet riser 19 communicating with the passage 18 for the escape of the hot gases, as will be hereinafter described.

60 The firebox 16 is constructed of two tubular sections A and B. The section A forms the main portion of the box, while the section B, which is at the inner end of the section A, is slightly smaller in diameter and has a frusto-conical end, whereby the outlet of the firebox is reduced (Figure 3). The firebox is lined with refractory material, such as plastic brick, or the like. The outer end of the section A is provided with a small Venturi opening 20 which receives the nozzle 21 of the burner 22.

65 The burner may be of any suitable structure and may either burn oil or gas as desired. The

force of the blower (not shown) of the burner is sufficient to mix the oil or gas being injected with a certain amount of oxygen and force this mixture through the Venturi opening 20 into the firebox, in which it is completely burned and then expelled therefrom through the reduced opening at the inner end of the section B.

The flue 17 has on one end a member 17' enlarged and engaging over the inner end of the firebox 16 and the hot gases are expelled thereinto. The member 17' is enlarged to prevent the extremely hot gases contacting the same and excessively heating the pipe and burning it out. The gases do not directly strike the flue 17 or 15 the enlarged member 17' until the force of the gases has been considerably lessened. The enlarged member is connected to the flue 17 by a reducing nipple or collar 15'. The flue comprises a plurality of longitudinal tubular metal pipes 23 which are suitably supported above the floor of the oven and are connected by elbows 23' at their ends so as to conduct the gases back and forth longitudinally over the floor of the oven. These pipes being of metal permit the heat from the 20 gases passing therethrough to radiate upwardly within the oven. The discharge end of the flue 17 is connected to the forward end of a transverse conductor 24 which comprises the return passage 18. This conductor extends rearwardly 25 contiguous to the side wall 11 of the oven through which the burner nozzle 21 extends.

By observing Figure 3, it will be seen that the conductor terminates in an enlarged housing 25 which is built around the outer end of the firebox so that the passage 18 communicates with the interior of the firebox 16 through the venturi 20. The rear end of the housing is connected with the outlet riser 19 which extends upwardly outside the rear wall of the oven.

40 In operation any suitable burner may be employed. The force of the fan or blower within the burner is employed to inject the fuel with a certain amount of oxygen into the firebox. Substantially complete combustion takes place 45 within the firebox and the hot gases are ejected from the box into the enlarged pipe member 17'. The reduced inner portion of the firebox prevents the hot gases from touching the metal wall of the pipe member 17' immediately upon release 50 from the firebox, whereby the force of the gases is considerably lessened before they contact the wall of said pipe. The particular frusto-conical shape of this inner end also tends to reflect a shadow in the immediate vicinity of the outlet 55 of the hot gases, which tends to kill "firebox reflection" and keep the outer end of the entire firing unit cooler.

The hot gases then travel from the rear of the oven through the flue 17 in the direction of the 60 arrows in Figure 3. During their travel the heat of the gases is radiated from the walls of the said flue and by the time said gases reach the passage 18, they have cooled considerably. These cooled gases pass rearwardly from the front of the oven 65 through the conductor 24 and into the enlarged housing 25 around the outer end of the firebox. The Venturi opening 20 in the outer end of the firebox not only provides a mixture of fuel and oxygen entering the firebox, but also vents or 70 sucks in a portion of the cooled gases which are passing through the housing 25 on their way to the outlet riser 19 which extends upwardly from the rear of said housing. These cooled gases which are drawn into the firebox are, of 75 course, reheated and recirculated through the

flue unit. Such of the cooled gases which are not drawn into the firebox, escape through the outlet riser 19.

The constant entrance of the cooled gases into the firebox keeps said box comparatively cool 5 and prevents overheating or burning out of the entire heating unit, thereby prolonging the life of said unit. The reheating of already cooled gases increases economy, without sacrificing efficiency and this is an important feature of the 10 invention. The injection of the cooled gases into the hot firebox brings about a heat exchange, whereby circulation is promoted and for this reason a recirculating fan or blower is not required. This unit produces a maximum 15 efficiency with a minimum of waste heat and its freedom from moving parts and auxiliary elements makes for its simplicity. It is pointed out that the firebox 16 is the only part of the 20 entire unit which is of refractory material, the flue 17 being formed of uninsulated metal, whereby radiation and efficiency is increased.

The recirculation of the cooled gases is accomplished automatically, the Venturi opening 20 being arranged to vent or suck in these gases 25 which pass by said opening through the housing 25. It has been found that the usual blower or fan on the ordinary burner has sufficient force to maintain circulation. It would be possible, however, to employ the ordinary city gas pressure 30 which is sufficient to maintain the required circulation.

The description which has been given recites more or less detail of a particular embodiment of the invention, which is set forth as new and useful; however, I desire it understood that the invention is not limited to such exact details of construction, because it is manifest that changes and modifications may be made, within the scope 35 of the appended claims.

What I claim and desire to secure by Letters Patent, is:

40 1. A heating unit for an oven comprising, a refractory firebox having an inlet orifice at one end and a reduced frusto-conical outlet at its 45 other end, means for injecting fuel into the box through the inlet opening, a metal flue connected with the outlet end of the box for receiving and circulating the hot combustion gases through an oven, the reduced frusto-conical end of the box 50 preventing the hot gases from contacting the metal wall of the flue immediately upon release from the box, and means for conducting the gases from the flue system past the inlet orifice of the firebox, whereby portions of these gases which 55 have been cooled by circulation are sucked into the firebox and reheated and recirculated.

2. In a heating unit, a firebox comprising, a circulating flue, a refractory cylindrical box having an inlet orifice at one end for receiving a 60 nozzle for injecting fuel into said box, the opposite end of the box having a reduced frusto-conical outlet opening, whereby the force of the 65 hot combustion gases ejected from the box is spent before contacting the wall of the flue which is connected to the outlet end of said firebox.

3. A heating unit for an oven comprising, a firebox including a cylindrical box having an orifice in its outer end for receiving a burner nozzle and having a reduced frusto-conical inner end, a flue connected to said inner end for circulating the hot combustion gases through an oven, means connected with the flue for conducting the gases after circulation through said system past the orifice of the firebox, said orifice 70 75

being constructed so as to draw portions of these gases which have been cooled by circulation into the firebox, whereby these portions are reheated and recirculated through the flue, and an outlet conductor for naturally releasing the remainder of the cooled gases to the atmosphere.

4. A heating unit for an oven comprising, a firebox including a cylindrical body having an orifice in its outer end for receiving a burner nozzle and having a reduced frusto-conical inner end, a flue connected to said inner end for circulating the hot combustion gases through an oven, a conductor connected with the flue for conducting the gases after circulation through said system past the orifice of the firebox, said orifice being constructed so as to draw portions of these gases which have been cooled by circulation into the firebox, whereby these portions are automatically reheated and recirculated through the flue without the aid of auxiliary means, and means connected with the conductor for the natural escape of the remainder of the

cooled gases from said conductor to the atmosphere.

5. A heating unit for an oven comprising, a sinuous circulating flue, a refractory firebox directly connected to one end of the flue for discharging hot gases directly into the flue, said box having an inlet at one end and a reduced frusto-conical outlet at the other end, said flue being so constructed that in cooperation with the reduced outlet of said box the hot gases are prevented from contacting the flue until the force thereof has been lessened, a burner extending into the inlet end of said box, and means for conducting heated currents from said flue and discharging the same to the atmosphere to create a natural draft through said flues, the flue having a by-pass extending across the inlet end of said fire-box, whereby a portion of said heated air currents are drawn into the inlet of said box for recirculation.
